OUTBOARD MOTOR STAND

Charles W. Tunstead, Minneapolis, Minn.

Application March 18, 1954, Serial No. 29,590

Term of patent 14 years

(Cl. D14—3)

Fig. 1

Fig. 2

To all whom it may concern:

Be it known that I, Charles W. Tunstead, a citizen of the United States, residing at Minneapolis, county of Hennepin, and State of Minnesota, have invented a new, original, and ornamental Design for an Outboard Motor Stand, of which the following is a specification, reference being had to the accompanying drawing, forming a part thereof.

Figure 1 is a perspective view showing one side of an outboard motor stand showing my new design, and;

Figure 2 is a perspective view of the opposite side of the same.

I claim:
The ornamental design for an outboard motor stand, as shown.
